CLAIM

The ornamental design for a wind controlled sprayer unit, as shown and described.

DESCRIPTION

FIG. 1 is a perspective view of a wind controlled sprayer unit showing my new design;

FIG. 2 is a front elevational view thereof;

FIG. 3 is a bottom plan view thereof;

FIG. 4 is a top plan view thereof; and

FIG. 5 is a right side elevational view thereof, the left side being a mirror image of the right side shown.
